UNITED STATES PATENT OFFICE.

GORDON LAND, OF OROVILLE, CALIFORNIA.

HYDROPNEUMATIC ELEVATOR OR INJECTOR.

No. 830,085.

Specification of Letters Patent.

Patented Sept. 4, 1906.

Application filed June 4, 1906. Serial No. 320,133.

To all whom it may concern:

Be it known that I, GORDON LAND, a citizen of the United States, residing at Oroville, Butte county, California, have invented 5 certain new and useful Improvements in Hydropneumatic Elevators or Injectors, of which the following is a specification.

My present invention relates to improvements in hydropneumatic jet elevators or 10 pumps for handling liquids, sand, gravel, and the like.

The object of the invention is to provide a simple and efficient construction in which air not under pressure may be introduced into 15 the center of the jet or injector.

The invention is illustrated in the accompanying drawings, in which—

Figure 1 is a central longitudinal section, and Fig. 2 a central section taken at right angles to Fig. 1.

Referring by reference-numerals to the drawings, 6 designates the suction-pipe through which the liquid, sand, or gravel is drawn, this suction-pipe being representative 25 of the usual or any desired form of suction-pipe.

9 represents a discharge-pipe, and 7 a Y branch connected at one end to the suction-pipe and having its branches at the opposite 30 end connected to corresponding branches of the injector or jet-chamber 8, which in its turn is connected to the discharge-pipe.

4 designates an injector-nozzle for the hydraulic jet, which projects into the center of 35 the chamber 8 axially in line with the discharge-pipe 9 and discharge-throat 5 of the chamber 8, the water under pressure for the hydraulic jet being introduced from a suitable pipe through a jet-chamber 3, made sepa- 40 rate from the nozzle 4 and of elbow form, as shown.

The numeral 1 designates an air-pipe which extends up through the elbow or jet chamber 3 and centrally through the jet-nozzle 4 and 45 is designed to permit the air at atmospheric pressure to be drawn through the same by the action of the hydraulic jet. This pipe is preferably provided with a check-valve 2 for preventing the escape of water therethrough 50 when the flow of water through the nozzle 4 is cut off or at any analogous time.

Heretofore great difficulty has been experienced in introducing air under pressure in 55 hydraulic pumps or elevators of this character, and wherever air has been introduced it

has generally been at the sacrifice of power and efficiency of the main jet. By introducing air in the center of the jet, as above described, I completely change the character of the introduction into the discharge-chamber 60 and the air while being drawn in at atmospheric pressure is placed under pressure in the discharge-chamber, where it is free to escape without the sacrifice of power.

The jet-chamber and nozzle 4 are both carried by a flanged ring 3^a, which is removably secured by bolts. By disconnecting the flanged ring the parts are rendered accessible, so that a larger or smaller air-jet may be substituted for that previously used. 65

Having thus described my invention, what I claim is—

1. A hydraulic injector comprising a suction-chamber, suction and discharge pipes communicating therewith, a hydraulic-injector nozzle projecting into the chamber, and an air-pipe in communication with the atmosphere and extending into the center of the chamber, substantially as described. 75

2. A hydraulic injector comprising a chamber, suction and discharge pipes communicating therewith, a hydraulic-injector pipe extending into the chamber and an air-pipe open to the atmosphere and extending centrally through the injector-nozzle into the 80 chamber, substantially as described.

3. In combination, a suction-pipe, a discharge-pipe, a chamber connected to the discharge-pipe and having side branches connected with the suction-pipe, a hydraulic-injector nozzle projecting into the chamber between the side branches and an air-pipe 85 extending through the injector-nozzle, substantially as described.

4. In combination, a suction-pipe, a discharge-pipe, a chamber connected to the discharge-pipe and having side branches connected with the suction-pipe, a hydraulic injector-nozzle projecting into the chamber between the side branches, and an air-pipe 90 extending through the injector-nozzle, said air-pipe communicating with the atmosphere and being provided with a check-valve, substantially as described. 95

In testimony whereof I affix my signature 100 in presence of two witnesses.

GORDON LAND.
